UNITED STATES PATENT OFFICE.

EDWARD L. C. MORSE, OF CHICAGO, ILLINOIS.

MAGAZINE PLATE-HOLDER FOR CAMERAS.

No. 927,063.

Specification of Letters Patent.

Patented July 6, 1909.

Application filed April 15, 1908. Serial No. 427,113.

To all whom it may concern:

Be it known that I, EDWARD L. C. MORSE, a citizen of the United States, residing at Chicago, in the county of Cook and State of Illinois, have invented certain new and useful Improvements in Magazine Plate-Holders for Cameras; and I do hereby declare the following to be a full, clear, and exact description of the invention, such as will enable others skilled in the art to which it appertains to make and use the same.

This invention relates to a novel construction in a magazine plate holder for cameras, the object being to provide a device of this character which will admit of the insertion and consecutive exposure of a relatively large number of plates and which is simple, easily operated, durable and efficient, and consists in the features of construction and combinations of parts hereinafter fully described and claimed.

In the accompanying drawings illustrating my invention: Figure —1— is a vertical section of a plate holder constructed in accordance with my invention on the line 1—1 of Fig. —4—. Fig. —2— is a plan section of the same on the line 2—2 of Fig. —1—. Fig. —3— is a vertical section on the line 3—3 of Fig. —1—. Fig. —4— is a vertical section on the line 4—4 of Fig. —1—. Fig. —5— is a longitudinal section of a small plate holder employed. Fig. —6— is a fragmentary front elevation of the small plate holder. Fig. —7— is a fragmentary detail perspective view of a guide employed. Fig. —8— is a fragmentary detail vertical section of the small plate holder.

The main object of my invention is to provide a magazine plate holder of maximum capacity in proportion to its size and which is very simple and easily operated.

Similarly to other magazine plate holders my device is equipped with two compartments from each of which plates are transferred to the other by externally actuated means, the main feature of novelty embodied in my invention residing in the construction whereby exposed plates are consecutively transferred from one compartment to the other and are replaced consecutively by unexposed plates transferred from the last named compartment to the first named, each compartment primarily receiving an equal number of plates.

In the accompanying drawings I have

illustrated a suitable embodiment of my invention without special regard to correct proportions, certain parts being shown relatively large and exaggeration being generally indulged in for purposes of clarity.

The device comprises a relatively flat rectangular box —1— equipped substantially midway between its ends with a partition wall —2— of less width than the depth of said box to provide slots —3— and —4— 60 bordering said partition wall on either side. Adjacent one side wall —5— of said box is a longitudinally disposed partition wall —6— which is cut away on opposite sides and at respectively opposite end portions to provide 70 longitudinal slots —7— and —8— establishing communication between the plate compartments —9— and —10— relatively and the compartment —11— in which the plate transferring mechanism is disposed. Said 75 slots —7— and —8— are disposed adjacent the front and rear walls of the box —1—, said front wall plate —12— being provided with the exposure opening —13— controlled 80 by the slide —14— movable in guide grooves 85 in the side walls of the box in the customary manner. The rear wall —15— of the box is preferably hinged to afford convenience of access to the compartment —10— for the insertion of plates. Each of the plates —16— 90 is disposed in a plate holder —17— preferably of sheet metal, said plate holders conforming in construction as closely as possible with the plate holders generally employed as far as the means for maintaining the plates in 95 proper position are concerned and each receiving only one plate instead of two. Said plate holders are equipped at opposite ends with inclined tongues —18— disposed substantially parallel with each other, said 100 tongues being adapted to serve as deflecting means or wedges whereby choking of the device is obviated as will hereinafter appear. The plate holders —17— contained in the lower compartment —9— are passed forward 105 by a flat spring —19— secured to the rear wall —15— and which preferably bears upon the middle of the rear wall of the last named plate holders, thus maintaining the foremost plate in position to be exposed when said 110 slide —14— is raised. It is, of course, essential that the device be so constructed that the plate to be exposed shall register with the normal position of the ground or focusing glass in the usual manner, but I have made

no attempt to properly illustrate the manner of accomplishing this end. The opening —13— is of less width than the plate holders —17—. The box 1 is also provided with a 5 supporting plate 20 disposed parallel with and above the bottom wall thereof, upon which the plate-holders 17 are supported and is likewise provided with a plate 21 disposed parallel with and below the top wall, said 10 plates being termed, for purposes of convenience, "false bottom" and "false top" respectively and serving to enable the plate shifting device to be moved to engage the plates to transfer the same. The foremost 15 plate holder —17— in the compartment —10— is borne upon at its side edge portions by flat springs —23— thus maintaining all of said plate holders and plates at the rearward limit of movement in said compartment. In the drawings the depth of the box is greatly exaggerated, showing too much free space. In practice the free space should not exceed in depth the space occupied by two plate holders —17—.

20 The plate shifting or transferring device consists of the plunger —24— longitudinally movable in a guide —25— secured to the outer wall of the compartment —11—, said plunger being capable of being rocked to a 25 limited extent in said guide. Said plunger projects through the upper wall of said box —1— and is equipped with a knob —26— for convenience. At its lower end and midway between its ends respectively said plunger is provided with oppositely disposed arms —27— and —28— each equipped at its 30 free end with a projection —29— adapted to pass through the slots —7— and —8— respectively, said arms being so disposed that 35 when said projection —29— of one thereof projects through one of said slots, the other thereof is withdrawn from the other slot.

Secured to the front and rear walls of the box —1— midway between the side wall 40 —5— and partition wall —6— thereof and at respectively opposite ends of the compartment —11— are guide strips —30— and —31— terminating at one end flush with the upper and lower faces of the partition wall 45 —2— respectively and terminating at their other ends flush with the false top and bottom of the box —1—. Said guide strips are so disposed as to prevent rocking movement of the plunger except when the latter reaches 50 the upper and lower limits of its movement respectively thereby serving to prevent either projection —29— of the arms —27— and —28— from passing out of engagement with a plate holder —17— after the latter 55 has been started from either compartment into the other. In order to prevent retrograde movement of said plunger until a plate shall have been moved the entire distance necessary to effect its transfer from one compartment to the other said guide strips are 60 equipped with yielding ratchet projections —32— relatively oppositely disposed and extending toward said partition wall —6— to engage the free end portions of said arms —27— and —28— as the projection —29— thereof respectively engages a plate holder —17— to transfer the same.

My device is operated as follows: The plates are primarily inserted in the plate holders —17— and the latter are then divided into two stacks of equal number and inserted face downward into the compartments —9— and —10—, the rear wall constituting a door being swung open for this purpose. After inserting the plate and closing and locking said rear wall or door (for which purpose the latch —33— is provided) the device is ready for use.

The box —1— is inserted in the camera in the same manner as an ordinary plate holder and after exposing the foremost plate in the compartment —9— the plunger —24— is rocked to throw the projection —29— of the arm —27— into operative position and said plunger is then pulled upwardly thereby 90 causing the plate holder —17— containing the exposed plate to pass through the slot —3— into the upper compartment —10— where it is forced by the springs against the foremost plate holder contained therein. 95 The said plunger cannot be lowered nor rocked until the movement necessary to fully effect transfer has been completed, thus preventing the operator from only partly transferring a plate and thus upon the next 100 succeeding exposure spreading his picture partially over two plates. After having thus transferred the exposed plate to the compartment —10— the operator rocks the plunger to throw the projection —29— of 105 the arm —28— into operative position relatively to the rearmost plate in said compartment —10— and by then returning said plunger to its primary position said plate is transferred to the compartment —9—. 110 These operations are repeated after each exposure until all plates have been exposed, it being obvious that thus each compartment always contains the same number of plates and that the possibility of error in operation 115 is entirely obviated.

No part of the operating mechanism can come into contact with the sensitized surfaces of the plates to scratch and mar the same and each plate is isolated from the 120 other so that the light cannot penetrate more than one of same at a time.

The means whereby the plate shifting device is maintained in engagement with the plate holder and is prevented from being reversed until transfer is fully effected constitutes the most essential feature of the invention. The said projections or tongues —18— of the plate holders —17— serve to force a plate holder which may accidentally 130

become lodged at an incline out of its path when moving from one compartment to another.

I claim as my invention:

1. A device of the kind specified, comprising a receptacle having two plate containing chambers communicating with each other through slots disposed adjacent the end walls of said chambers and through which plates are adapted to pass from one to the other, springs forcing the said plates in respective chambers in opposite directions, a rocking plunger reciprocally movable in guides in said receptacle, and oppositely disposed projections on said plunger adapted when the latter is turned to be respectively thrown into and out of engaging relation to the plates in the respective compartments, as and for the purpose specified.
2. A device of the kind specified, comprising a receptacle having two plate containing chambers communicating with each other through slots disposed adjacent the end walls of said chambers and through which plates are adapted to pass from one to the other, plate holders isolating said plates from each other, springs forcing the said plates in respective chambers in opposite directions, a rocking plunger reciprocally movable in guides in said receptacle, and oppositely disposed projections on said plunger adapted when the latter is turned to be respectively thrown into and out of engaging relation to the plates in the respective compartments, as and for the purpose specified.
3. A device of the kind specified, comprising in combination a receptacle having two plate containing chambers communicating with each other through slots disposed adjacent the front and rear walls thereof respectively, a spring mounted upon the rear wall of one chamber and bearing upon the rearmost plate to move all the plates contained therein to the forward limit of their movement, a similarly acting spring mounted upon the front wall of the other chamber, and an externally operable plate shifting device reciprocally movable and adapted to consecutively engage plates contained in the lower chamber when moved in one direction and similarly engage plates contained in the upper chamber when moved in the opposite direction to alternately move said plates of said respective chambers through said slots and between the springs and plates in the chamber receiving each plate.
4. A device of the kind specified, comprising in combination a receptacle having two plate containing chambers communicating with each other through slots disposed adjacent the front and rear walls thereof respectively, plate holders isolating said plates from each other, a spring mounted upon the rear wall of one chamber and bearing upon the rearmost plate to move all the plates con-
- tained therein to the forward limit of their movement, a similarly acting spring mounted upon the front wall of the other chamber, and an externally operable plate shifting device reciprocally movable and adapted to 70 consecutively engage plates contained in the lower chamber when moved in one direction and similarly engage plates contained in the upper chamber when moved in the opposite direction to alternately move said plates of 75 said respective chambers through said slots and between the springs and plates in the chamber receiving each plate.
5. A device of the kind specified, comprising in combination a receptacle having two 80 plate containing chambers communicating with each other through slots disposed adjacent the front and rear walls thereof respectively, a spring mounted upon the rear wall of one chamber and bearing upon the rear- 85 most plate to move all the plates contained therein to the forward limit of their movement, a similarly acting spring mounted upon the front wall of the other chamber, a chamber bordering both said plate containing chambers, and communicating with the latter through slots disposed at opposite sides and ends of the partition wall separating said chambers respectively, a reciprocating plunger movable in said last-named 90 chamber, and oppositely disposed projections at one end and between the ends respectively of said plunger, said projections being adapted to project through slots in the dividing walls between the plate-chambers and 100 the plunger chamber to engage and project plates from one plate-chamber into the other, said shaft being rocked to throw either of said projections into engaging relation to the plates.
6. A device of the kind specified, comprising in combination a receptacle having two plate containing chambers communicating with each other through slots disposed adjacent the front and rear walls thereof respectively, a spring mounted upon the rear wall of one chamber and bearing upon the rear- 110 most plate to move all the plates contained therein to the forward limit of their movement, a similarly acting spring mounted 115 upon the front wall of the other chamber, a chamber bordering both said plate containing chambers, and communicating with the latter through slots disposed at opposite sides of the partition wall separating said 120 chambers respectively, a reciprocating plunger movable in said last-named chamber, and oppositely disposed projections at one end and between the ends respectively of said plunger, said projections being adapted to 125 project through slots in the dividing walls between the plate-chambers and the plunger chamber to engage and project plates from one plate-chamber into the other, said shaft being rocked to throw either of said projec- 130

tions into engaging relation to the plates and means operatively disposed relatively to the said projections and maintaining the same in said engaging relation to said plates during a given movement of the said plunger.

7. A device of the kind specified, comprising in combination a receptacle having two plate containing chambers communicating with each other through slots disposed adjacent the front and rear walls thereof respectively, a spring mounted upon the rear wall of one chamber and bearing upon the rearmost plate to move all the plates contained therein to the forward limit of their movement, a similarly acting spring mounted upon the front wall of the other chamber, a chamber bordering both said plate containing chambers, and communicating with the latter through slots disposed at opposite sides and ends of the partition wall separating said chambers respectively, a rocking plunger reciprocally movable in said last-named chamber, a projection between the ends of said plunger, an oppositely disposed projection at one end of said plunger, said projections being relatively so disposed that when said plunger is turned one thereof is thrown into engaging relation to the plates in one of said compartments to transfer the same when said plunger is moved longitudinally in one direction and vice versa, and means operatively engaging said projections to maintain the operating one thereof in its engaging relation to the plates throughout the longitudinal movement of the plunger in one direction.
8. A device of the kind specified, comprising in combination a receptacle having two plate containing chambers communicating with each other through slots disposed adjacent the front and rear walls thereof respectively, a spring mounted upon the rear wall of one chamber and bearing upon the rearmost plate to move all the plates contained therein to the forward limit of their movement, a similarly acting spring mounted upon the front wall of the other chamber, a chamber bordering both said plate containing chambers, and communicating with the latter through slots disposed at opposite

sides and ends of the partition wall separating said chambers respectively, and externally operable rocking plate shifting means movable in said last named chamber equipped with projections passing through said last named slots and engaging said plate holders to impart movement thereto to transfer the same from one of said plate containing chambers to the other thereof, said projections to maintain one thereof in engagement with a plate holder between the limits of longitudinal movement of said plate shifting device.

9. A device of the kind specified, comprising in combination a receptacle having two plate containing chambers communicating with each other through slots disposed adjacent the front and rear walls thereof respectively, a spring mounted upon the rear wall of one chamber and bearing upon the rearmost plate to move all the plates contained therein to the forward limit of their movement, a similarly acting spring mounted upon the front wall of the other chamber, a chamber bordering both said plate containing chambers, and communicating with the latter through slots disposed at opposite sides and ends of the partition wall separating said chambers respectively, and externally operable rocking plate shifting means movable in said last named chamber equipped with projections passing through said last named slots and engaging said plate holders to impart movement thereto to transfer the same from one of said plate containing chambers to the other thereof, said projections to maintain one thereof in engagement with a plate holder between the limits of longitudinal movement of said plate shifting device.

In testimony whereof I have signed my name in the presence of two subscribing witnesses.
